FRANK L. CROSS, OF MYSTIC, CONNECTICUT, ASSIGNOR TO CROSS PAPER FEEDER COMPANY, OF BOSTON, MASSACHUSETTS, A CORPORATION OF MAINE.

PAPER-CUTTING MACHINE.

No. 826,480.

Specification of Letters Patent.

Patented July 17, 1906.

Application filed July 19, 1902. Serial No. 116,193.

To all whom it may concern:

Be it known that I, FRANK L. CROSS, of Mystic, in the county of New London and State of Connecticut, have invented certain new and useful Improvements in Paper-Cutting Machines, of which the following is a specification.

The invention relates to paper-cutting machines, and more especially to the mechanism for clamping and holding the paper during the cutting.

It is desirable in paper-cutting machines that the clamp be forced down upon the paper with substantially the full clamping pressure prior to the engagement of the knife with the paper, so that the top sheet shall not be drawn or displaced by the action of the knife in beginning the cut. The clamping pressure should also be continued until the cutting is completed, so that the bottom sheets may not be displaced. It is also desirable that the clamping pressure may be readily varied for different kinds of work. In order that a machine may be operated with accuracy and certainty, it is also important that the clamping pressure should be uniform during the cut and also the same for successive cuts while operating upon the same class of work and with a given adjustment of the parts. Automatic clamping-cutters have not fulfilled these conditions, and for that reason it has been customary to employ hand-operated clamps upon machines for doing certain classes of work where accuracy and certainty in the clamping and cutting are important. The reason for this is that in these automatic clamping-machines the clamping pressure was either dependent upon the resistance offered to the knife by the paper or was dependent upon the frictional connection between the members of a friction-clutch. In the first case the clamping did not precede the engagement of the knife with the paper and the clamping pressure varied during the cutting, with the resulting uncertainty and danger of inaccuracy in the operation. In the second case there was no certainty and uniformity of action, owing to the wide and unavoidable variation in the resistance required to cause a friction-clutch to slip, even when the conditions are as nearly uniform as practicable.

The object of the invention is to provide a cutter in which the clamp is automatically

operated to clamp the paper with a pressure which shall be definite and uniform for successive operations and which is therefore adapted for use under the conditions and for the classes of work which heretofore required machines having hand-operated clamps. 55

To this end the primary feature of the invention consists in providing mechanism for automatically operating the clamp which is thrown out of action when the pressure between the clamp and paper reaches an 65 amount which is definite and unvarying for any given adjustment.

The means which I prefer to employ for throwing the clamp-operating mechanism out of operation comprises a movable part 70 introduced into the connections between the driver and the clamp, the movement of which relatively to the other parts of the connections is at each operation dependent upon an unvarying and definite resistance to the 75 movement of the clamp and which by its movement causes the driver to be disconnected and the operating mechanism to be thus thrown out of operation. The form and arrangement of this movable part is immaterial so far as the broad scope of my invention is concerned, as I believe I am the first to insure a definite clamping pressure by mechanism which automatically operates the clamp and that I am also the first to disconnect the driver for the clamp-operating mechanism by a part the movement of which to disconnect the driver requires a pressure between the clamp and paper which is unvarying for a given adjustment and may be 80 predetermined. After the clamp has been applied with the predetermined pressure, it may be held in this position by any suitable devices, and these devices may be either included in the connections between the driver 85 and clamp or may be arranged outside said connections, and these devices may act merely to lock the clamp in position or may act to maintain an active pressure on the clamp. I prefer to construct and arrange these devices so 90 that there is an active pressure on the clamp equal to the clamping pressure, or, in other words, I prefer to maintain the pressure of the clamp upon the paper during the cutting, so that any compression of the paper by the 95 knife will not act to relieve the pressure of the clamp, as might happen under some conditions if the clamp were merely locked in po- 100 105

sition. This construction and arrangement of the devices for holding the clamp upon the paper also forms one of the features of my invention, which while it is not essential to the 5 primary feature is important in insuring the most efficient and accurate operation under all conditions.

A further feature consists in so constructing the devices which determine the clamping pressure requisite for throwing out the operating mechanism that they may be readily adjusted to vary the pressure for different classes of work and varying conditions. In combining these features with the primary 15 feature of the invention I prefer to provide counterbalancing means—such, for instance, as a weight or spring—for resisting the movement of the movable part which throws out the clamp-operating mechanism and to so arrange this means that it will yield when the 20 pressure between the clamp and paper overbalances the force of the counterbalancing means. The yielding of the counterbalancing means allows the movable part to move 25 and by its movement to throw out the clamp-operating mechanism, after which the pressure of the clamp is maintained by the counterbalancing means acting to force the clamp onto the paper with a pressure substantially 30 equal to the pressure which caused the yielding of said means. This arrangement also lends itself readily to the variation of the clamping pressure for different classes of work, since by adjusting the counterbalancing 35 means to offer a greater or less resistance to the movement of the movable part the clamping pressure is varied. With this construction, in which the spring or weight measures and determines the clamping pressure, it 40 is evident that the clamping pressure may be accurately regulated and that at each operation the clamping pressure will be the same definite amount. It is also evident that with 45 the spring or weight arranged to react upon the clamp when the operating mechanism is thrown out a uniform pressure upon the paper will be maintained throughout the cutting operation. In embodying these main 50 features of my invention in an automatic cutting-machine I have employed other features of invention which are not essential to the main features, but which contribute to the efficiency and simplicity of the machine.

The various features of the invention will 55 be best understood from a detailed description of this machine, which I have illustrated in the accompanying drawings, in which—

Figure 1 is a front elevation. Fig. 2 is a 60 sectional elevation, the section plane being just inside the left end frame, Fig. 1. Fig. 3 is a plan view with the paper-supporting table removed, and Fig. 4 is a detail view of mechanism to be described.

In the drawings, A indicates the knife-bar, 65 mounted in guides in the end frames of the

machines. The knife-bar is supported and carried by yokes A', provided with rolls A², which engage slots A³, formed in the bar, the upper ends of the yokes engaging the top of the bar. As the bar is drawn down it is 70 moved transversely to give a draw cut by means of a link A⁴, pivoted to the bar and frame. The yokes A' are connected by links A⁵ with the ends of arms A⁶, which are secured to a rock-shaft A⁷. The shaft A⁷ is 75 rocked to reciprocate the knife-bar by means of a crank A⁸, carried by a gear A⁹ and engaging a slot A¹⁰, formed in an arm A¹¹, secured to the shaft A⁷. The gear A⁹ is driven through a pinion A¹², loosely mounted upon the driving-shaft B and connected with one member of a clutch A¹³. The other member of the clutch is secured to the driving-shaft B, and the clutch is engaged and disengaged by the movement of a cone A¹⁵, arranged to 80 operate upon the clutch-arms A¹⁶. The clutch-operating cone A¹⁵ is moved by means of a yoke A¹⁷, loosely mounted on a shaft a³ and provided with arms engaging an annular groove in the cone A¹⁵. The yoke is 85 operated to engage the clutch A¹³ by the movement of a hand-lever A¹⁸, secured to a rock-shaft A¹⁹, which is connected with the yoke A¹⁷ by means of an arm A²⁰, having a slot which engages a pin A²¹ on the yoke. By 90 operating the handle A¹⁸ the clutch A¹³ may be engaged to connect pinion A¹² with the driving-shaft, and thus start the knife-operating mechanism. After the gear A⁹ has 95 made a revolution and the knife-bar has 100 been drawn down and returned to its upper position the yoke A¹⁷ is moved in the opposite direction to disengage the clutch by means of a pawl a, carried by an arm a' and arranged to engage a pin a², Fig. 2, on the 105 yoke. The arm a' is secured to the rock-shaft a³, which is operated from the knife-operating arm A¹¹ by means of an arm a⁴, secured to the shaft and connected to the upper end of a rod a⁵, the lower end of which 110 passes through a lug a⁶ on the arm A¹¹ and carries nuts a⁷. The nuts a⁷ are so adjusted that as the knife-bar reaches its upper position the lug a⁶ strikes the nuts and draws down rod a⁵, thus rocking shaft a³. This 115 movement of shaft a³ carries pawl a to the left, thus disengaging clutch A¹³. The lug a⁶ now prevents any movement of shaft a³ in the opposite direction until the arm A¹¹ has been started upward. The pawl a must 120 therefore be disengaged from the pin a² to allow the yoke A¹⁷ to be moved to the right in starting the knife-operating mechanism. This is done automatically by a cam-surface a⁸, arranged to engage the end of a screw 125 a⁹ as the pawl moves to the left and lift the pawl out of engagement with the pin a². When the arm A¹¹ has started up and released the shaft a³, the shaft is rocked to carry the pawl into engagement with the pin a² by rea- 130

son of the connection of the shaft a^3 with mechanism to be described.

The driving-shaft is provided with a tight pulley B' and a loose pulley B^2 for carrying 5 the driving-belt, through which power is supplied to drive the machine.

The paper is held during the action of the knife by means of a clamp C , mounted in guides C' in the end frames and secured to 10 the upper end of bars C^2 . The clamp is raised and is held in a raised position by the action of a weight C^3 , acting through suitable connections. The weight is secured to an arm C^4 , which projects rearwardly from a 15 treadle C^5 , loosely mounted on the shaft A^7 . The treadle is connected by a link C^7 with an arm C^8 , secured to a rock-shaft C^9 , which carries arm C^{10} , the outer ends of which are provided with slots engaging pins C^{11} on the 20 bars C^2 . By operating the treadle the clamp may be brought down upon the paper and will be returned by the weight when the treadle is released.

The mechanism for operating the clamp automatically is connected with the clamp through the bars C^2 , which are provided with rack-teeth at their lower ends arranged to be engaged by pinions c' , secured to a shaft c . The shaft c is connected with and disconnected 25 from the other parts of the clamp-operating mechanism by means of a clutch, one member c^3 of which is keyed to slide on the shaft c and the other member of which is formed on a worm-wheel c^2 , loose on the shaft. 30 The clutch-sleeve c^3 is pressed toward the worm-wheel by a spring c^4 and is moved against the tension of the spring to disengage the clutch by a lever c^6 , having arms c^5 , which engage an annular groove in the clutch-sleeve. 35 The engagement and disengagement of the clutch is controlled from the knife-operating mechanism. For this purpose the lever c^6 is connected by a rod c^7 with an arm c^8 , secured to shaft a^3 , so that when the 40 shaft a^3 is rocked by the engagement of lug a^6 with nuts a^7 the clutch-sleeve c^3 will be moved out of engagement and held out against the tension of spring c^4 until the arm A^{11} starts upward again, when the spring c^4 will engage 45 the clutch-sleeve. This movement of the sleeve c^3 will rock shaft a^3 and carry pawl a' into engagement with pin a^2 preparatory to the disengagement of clutch A^{13} . Thus the 50 clutch-sleeve c^3 is engaged with the worm-wheel as the knife-operating mechanism starts and is disengaged to allow the clamp to return to its upper position as the knife-bar reaches its upper position.

The worm-wheel c^2 is engaged and operated by a worm D , secured to a shaft D' . This shaft and worm are so mounted that they may have a limited longitudinal movement, and they are one form of yielding part introduced into the connections between the 55 driver and the clamp for throwing the clamp-operating mechanism out of operation. The longitudinal movement of the shaft D' is resisted by the pressure of an arm F on the end of the shaft. This arm is secured to a shaft F' , and the pressure which it will apply to the 70 end of the shaft D' depends upon weights F^2 , secured upon arms F^3 , which are secured to the shaft F' . One or more arms F^3 and weight F^2 may be used and by adjusting the weight on the arm the resistance offered to 75 the longitudinal movement of shaft D' may be varied as desired. When the shaft D' is rotated, the clamp will be drawn down upon the paper, and when the clamp engages the paper the resistance to the movement of the 80 clamp will create an endwise thrust on the worm D , which thrust will be proportional to the pressure between the clamp and paper. This thrust is resisted by the weight F^2 acting through the arms F^3 and F , and the clamp 85 will continue to be forced down onto the paper until this thrust is sufficient to lift weight F^2 , after which continued rotation of shaft D' will cause a longitudinal movement of the shaft and a movement of arms F F^3 90 and weight F^2 . The weight and connections therefore are one form of means for resisting the movement of the yielding part which control the throwing out of the clamp-operating mechanism with a definite and regulated pressure. The resistance offered by 95 the weight is definite and is the same each time the clamp is operated, and therefore the clamp will always be applied to the paper with a definite and fixed pressure, dependent 100 upon the size and adjustment of the weight. The driver for operating the clamp consists of a clutch D^3 , one member of which is loosely mounted on the shaft D' and the other member of which is secured to the shaft. 105 The loose member is connected with a spiral gear D^2 , engaged and continuously driven by engagement with a spiral gear D^7 , secured to a shaft D^6 , which carries a spiral gear D^8 , engaged by a spiral gear D^9 , secured to the 110 driving-shaft B . The clutch D^3 is engaged and disengaged by the movement of a cone D^4 , arranged to engage the operating-arms D^5 of the clutch. The longitudinal movement of the shaft D' serves to operate the 115 cone D^4 to disengage the clutch, and thus throw the clamp-operating mechanism out of operation. To effect this, an arm F^6 is secured to the shaft F' , and the end of this arm is connected, by means of a link F^5 , with one 120 end of a bell-crank lever F^4 , the other end of which is provided with arms engaging an annular groove in cone D^4 . When the shaft D' is moved longitudinally by reason of the pressure between the clamp and paper, the shaft 125 F' is rocked and the clutch D^3 disengaged. The pressure of the clamp is now maintained by the action of the weight F^2 and the connections between said weight and the clamp, the worm D acting as a rack and the worm- 130

wheel as a gear to transmit the pressure applied to the shaft. Thus the clamp is forced onto the paper during the cutting with full clamping pressure. As the knife-bar reaches 5 its upper position an arm F⁷, secured to shaft A⁷, strikes the end of a screw F⁸, mounted in an arm F⁹, secured to shaft F' and rocks the shaft F' against the action of weight F². This relieves the pressure upon the connec- 10 tions between the shaft D' and the clamp, so that the clutch-sleeve c³ may be readily disengaged from the worm-wheel c² to allow the clamp to return to normal position. When the knife-operating mechanism is started, 15 the arm F' moves away from screw F⁸, thus causing the pressure to be applied to the end of shaft D'.

In the machine described the clamp-operating mechanism is controlled from the knife-operating mechanism and is coupled with the clamp by the same mechanism which throws the clamp into operation, so that all the operations are automatically performed whenever the operator 20 throws the knife-operating mechanism into 25 operation. It will be understood, however, that this arrangement is not essential, although it is advantageous in saving time. By reason of the fact that the automatic 30 mechanism for operating the clamp is disconnected for the return of the clamp the operator may bring the clamp down upon the paper by pressing on the treadle before starting the machine, and thus avoid any danger of dis- 35 placement of the sheets by the sudden engagement of the clamp with the paper. This is of importance in doing some classes of work.

The parts are so timed that the clamp will engage the paper and the clutch D³ be disengaged before the knife strikes the paper, and the paper will be clamped with full clamping pressure therefore before it is engaged by the knife. By varying the position of the weight F² the clamp may be made to clamp the paper with any desired force, and when the weight has been once adjusted for a certain 40 clamping pressure the clamp will be applied to the paper with this pressure at each operation of the machine, thus enabling the paper 45 to be clamped with even a greater degree of certainty and accuracy than has heretofore been practicable with hand-operated clamps and without loss of time or the exercise of skill or care on the part of the operator.

55 What I claim, and desire to secure by Letters Patent, is—

1. In a paper-cutting machine the combination of a clamp, mechanism for automatically operating said clamp to clamp the paper and mechanism for throwing said operating mechanism out of action when the clamping pressure reaches an unvarying definite or predetermined amount, substantially as described.

65 2. In a paper-cutting machine the combi-

nation of a clamp, mechanism for automatically forcing the clamp upon the paper including a movable part each operative movement of which requires the same definite pressure between the clamp and paper, and means whereby the movement of said part throws said mechanism out of operation, substantially as described.

3. In a paper-cutting machine the combination of a clamp, mechanism for automatically operating said clamp to clamp the paper, mechanism for throwing said operating mechanism out of action when the clamping pressure reaches a definite or predetermined amount, and for actively maintaining said pressure during the cutting, substantially as described.

4. In a paper-cutting machine the combination of a clamp, mechanism for automatically forcing the clamp upon the paper including a yielding part through which pressure is transmitted to the clamp, means for resisting the yielding of said part with a definite and regulated force whereby the pressure of the clamp upon the paper is defined and measured, substantially as described.

5. In a paper-cutting machine the combination of a clamp, mechanism for automatically forcing the clamp upon the paper including a yielding part through which pressure is transmitted to the clamp, means for resisting the yielding of said part with a definite and regulated force, whereby the pressure of the clamp upon the paper is defined and measured, and means for adjusting said force to vary the clamping pressure, substantially as described.

6. In a paper-cutting machine the combination of a clamp, mechanism for automatically forcing the clamp upon the paper including a yielding part through which pressure is transmitted to the clamp, means for resisting the yielding of said part with a definite and regulated force whereby the pressure of the clamp upon the paper is defined and measured, a driver for said mechanism and means controlled by the movement of said yielding part for disconnecting said driver, substantially as described.

7. In a paper-cutting machine the combination of a clamp, a driver and connections for automatically forcing the clamp upon the paper, and means dependent for its operation upon an unvarying and definite resistance to the clamp for disconnecting said driver, substantially as described.

8. In a paper-cutting machine the combination of a clamp, mechanism for automatically forcing the clamp upon the paper, a driver therefor, mechanism for disconnecting said driver when the clamping pressure reaches an unvarying definite or predetermined amount and means for holding the clamp in position during the cutting, substantially as described.

9. In a paper-cutting machine the combination of a clamp, a driver, connections between said driver and clamp including a worm-wheel and a worm mounted to move longitudinally, means for forcing said worm longitudinally with a definite force, and means operated through the longitudinal of the worm against said force for disconnecting said driver, substantially as described.
10. In a paper-cutting machine the combination of a clamp, a driver, connections between the driver and clamp including a worm-wheel and a worm mounted to move longitudinally, an adjustable weight for applying pressure to move said worm longitudinally, and means for disconnecting said driver through the movement of said worm against the pressure of said weight, substantially as described.
11. In a paper-cutting machine the combination, of a paper-cutting knife, operating mechanism for the knife, a paper-holding clamp, clamp-operating means, and automatical controlling means adapted to effect the operative connection between the clamp and its operating means for moving the clamp into engagement with the pile of sheets and to automatically disconnect the clamp from its operating means when the clamping pressure reaches an unvarying definite amount, substantially as described.
12. In a paper-cutting machine, the combination of a paper-cutting knife, operating mechanism for the knife, a paper-holding clamp, clamp-operating means, automatic controlling means adapted to effect the operative connection between the clamp and its operating means for moving the clamp into engagement with the pile of sheets and then automatically disconnect the clamp from its operating means when the clamping pressure reaches an unvarying definite amount, and means for automatically disengaging the clamp from the pile of sheets after the completion of the cutting operation, substantially as described.
13. In a paper-cutting machine, the combination of a pile-supporting table, a paper-cutting knife, means for operating said knife, a paper-holding clamp, operating mechanism adapted to move the clamp into engagement with the pile and then automatically disengage itself from the clamp, and means for maintaining an active pressure on the clamp during the cutting, substantially as described.
14. In a paper-cutting machine, the combination of a pile-supporting table, a paper-cutting knife, means for operating said knife, a paper-holding clamp, clamp-operating means, and means for counterbalancing the pressure between the clamp and paper adapted to automatically disconnect the clamp-operating means from the clamp when overbalanced by said pressure, substantially as described.
15. In a paper-cutting machine the combination of a pile-supporting table, a paper-cutting knife, knife-operating mechanism, a paper-holding clamp, clamp-operating mechanism having a yielding part, counterbalancing means resisting the yielding of said part, and means actuated by the yielding of said part adapted to automatically disconnect the clamp from its operating mechanism, substantially as described.
16. In a paper-cutting machine the combination of a pile-supporting table, a paper-cutting knife, its operating mechanism, a paper-holding clamp, suitable clamp-operating mechanism having a yielding part, counterbalancing means resisting the movement of said part, means actuated by the yielding of said part of the operating mechanism adapted to automatically disconnect the clamp from its operating mechanism, and means for automatically raising the clamp from the pile after the completion of the cutting operation, substantially as described.
17. In a paper-cutting machine the combination of a clamp, mechanism for automatically forcing the clamp upon the paper, a counterbalancing device for determining the pressure between the clamp and paper, and mechanism for disconnecting the clamp and operating mechanism upon the yielding of the counterbalancing device, substantially as described.
18. In a paper-cutting machine the combination of a clamp, mechanism for automatically forcing the clamp upon the paper including a yielding part through which pressure is transmitted to the clamp, and a counterbalancing device for determining said pressure, substantially as described.
19. In a paper-cutting machine the combination of a clamp, mechanism for automatically forcing the clamp upon the paper including a yielding part through which pressure is transmitted to the clamp, and an adjustable counterbalancing device for determining said pressure.
20. In a paper-cutting machine the combination of a cutting-knife, knife-operating mechanism, a clamp, and mechanism automatically forcing the clamp against the work with the same definite pressure at successive operations, substantially as described.
21. In a paper-cutting machine the combination of a cutting-knife, knife-operating mechanism, a clamp, mechanism automatically forcing the clamp against the work with the same definite pressure at successive operations, and means for regulating said pressure, substantially as described.
22. In a paper-cutting machine the combination of a cutting-knife, knife-operating mechanism, a clamp, mechanism automatically forcing the clamp against the work with the same definite pressure at successive operations, and mechanism for automatically re-

6
turning the clamp after the cutting is completed, substantially as described.

23. In a cutting-machine having supporting-frames and a work-table attached thereto, 5 a driving-shaft revolubly mounted in bearings in said supporting-frames; auxiliary shafts revolubly mounted in said supporting-frames and driven from said driving-shaft by means of clutches mounted thereon; a 10 clamping-bar slidably mounted in said supporting-frames and operated by one of said auxiliary shafts; means on said auxiliary shafts for adjusting the amount of pressure exerted by said clamping-bar; means mounted 15 on said auxiliary shaft for automatically stopping the movement of said clamping-bar when a predetermined pressure is exerted by it; a cutter-bar slidably mounted in said supporting-frames and driven by the other auxiliary shaft; means on said auxiliary shaft for 20 causing said cutter-bar to move toward the table to cut material placed thereon and to return to its normal position, and to automatically stop said auxiliary shaft when said cutter-bar has been returned to its normal inoperative position; and means operated by said 25 cutter-bar for returning the clamping-bar to its normal inoperative position.

24. In a paper-cutting machine the combination of supporting-frames, a work-table attached thereto, a main driving-shaft revolubly mounted in bearings in said supporting-frames, intermediate shafts driven by said driving-shaft, clutches mounted on said main shafts and driving-shaft, a clamping-bar slidably mounted in said supporting-frame and arranged to clamp the material to be cut between it and the work-table, means for throwing said intermediate shafts into operation, 30 means operable by said intermediate shafts for causing the clamping-bar to be drawn toward the table, and means independent of the cutter-bar operable by a counterbalancing device whereby a given pressure exerted 35 upon the material to be cut by said clamping-bar will automatically stop its further movement.

25. In a paper-cutting machine the combination of supporting-frames, a work-table attached thereto, a main driving-shaft revolubly mounted in bearings in said supporting-frame, means for revolving said main driving-shaft, intermediate shafts mounted in said supporting-frames and driven from said main driving-shaft, a cutter-bar slidably mounted 40 in said supporting-frames, counterbalancing means acting on one of said intermediate shafts for producing a predetermined pressure upon the material to be clamped, means whereupon the material to be clamped, means where- 45 by said cutter-bar will be moved toward and from the work-table when said predetermined

pressure has been exerted, and means for automatically stopping its movement when returned to its normal inoperative position.

26. In a paper-cutting machine the combination of supporting-frames and a work-table mounted thereon, a main driving-shaft revolubly mounted in bearings in said supporting-frames, auxiliary shafts revolubly mounted in said supporting-frames and driven from 50 said main shaft, a clamping-bar and a cutter-bar slidably mounted in said supporting-frame and adapted to be moved toward and from the work-supporting table to clamp and cut material placed thereon, automatic means 55 intermediate said main driving-shaft and said clamping and cutting bars arranged to cause them to perform the following cycle of operations to wit, a counterbalancing device and means to cause the clamping-bar to automatically move toward the table and clamp material placed thereon with a predetermined pressure and thereafter to cause the cutter-bar to move toward the table and cut the material thereon, and means whereby 60 both the cutter-bar and the clamping-bar will automatically return to their normal inoperative position and remain there until it is desired to make the next cycle of operations.

27. In a paper-cutting machine the combination of supporting-frames and a suitable table attached thereto, an automatic clamping and cutting mechanism comprising a clamping-bar and a cutter-bar slidably mounted in 65 said supporting-frames, and a single operating-lever, controlling means and a counterbalancing device for causing the clamping-bar to move toward the work-table and to clamp the material to be cut with a predetermined pressure, and means whereby the cutter-bar will be caused to move toward the table and cut the material after a predetermined pressure exerted by the clamping-bar, and means operated from the driving-shaft to cause said cutter-bar and clamping-bar to automatically return to their normal inoperative positions.

28. In a paper-cutting machine the combination of a clamping-bar, a worm-shaft capable of moving longitudinally in one direction, means for imparting a vertical movement to the clamping-bar operated by the worm-shaft, a counterbalancing device resisting the longitudinal movement of the worm-shaft, and means for driving and stopping the worm-shaft.

In testimony whereof I have affixed my signature in presence of two witnesses.

FRANK L. CROSS.
